UNITED STATES PATENT OFFICE

110,268

DESIGN FOR A COMBINED STORAGE CABINET AND DISPLAY SCREEN

Albert S. Carman, New York, N. Y., assignor to
The Dentists' Supply Company of New York,
New York, N. Y., a corporation of New York

Application February 28, 1938, Serial No. 75,461

Term of patent 7 years

To all whom it may concern:

Be it known that I, Albert S. Carman, a citizen of the United States, and a resident of Manhattan, in the county of New York and State of New York, have invented a new, original, and ornamental Design for a Combined Storage Cabinet and Display Screen, of which the following is a specification, reference being had to the accompanying drawings, forming a part thereof.

Figure 1 is a front elevational view of the combined storage cabinet and display screen showing my new design,

Figure 2 is a side elevational view of the same, Figure 3 is a side elevational view showing the rear door dropped and the sliding base extended, and

Figure 4 is a front elevational view with the front doors open to illustrate the projection screen immediately behind said doors.

I claim:

The ornamental design for a combined storage cabinet and display screen, as shown and described.

ALBERT S. CARMAN.
